[57] CLAIM

The ornamental design for a combined hand held computer stand and handle, as shown and described.

DESCRIPTION

FIG. 1 is a perspective view of a combined hand held computer, stand, and handle in the closed, carrying position showing our new design;

FIG. 2 is a perspective view thereof, wherein the stand and handle are in the opened position;

FIG. 3 is a right side elevational view thereof;

FIG. 4 is a rear elevational view thereof;

FIG. 5 is a bottom plan view thereof;

FIG. 6 is a left side elevational view thereof.

FIG. 1.

FIG. 2.

FIG. 3.

FIG. 4.

FIG. 6.

FIG. 5.
